UNITED STATES PATENT OFFICE.

ALBERT R. ROBERTS AND GEORGE T. SMITH, OF CHATTANOOGA, TENNESSEE.

BEVEL SHEARING MACHINE.

1,426,216.

Specification of Letters Patent. Patented Aug. 15, 1922.

Application filed September 15, 1920. Serial No. 410,384.

To all whom it may concern:

Be it known that we, ALBERT R. ROBERTS and GEORGE T. SMITH, citizens of the United States, residing at Chattanooga, in the county of Hamilton and State of Tennessee, have invented a new and useful Bevel Shearing Machine, of which the following is a specification.

This invention relates to bevel shearing machines of the type which employ rotary cutters.

The object of the invention is to provide such a machine which will bevel the edges of plates, sheet metal bars, and all structural steel in opposite directions without necessitating the turning of the plates, bars or the like over or end for end.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

30 In the drawing:—

Fig. 1 is a vertical longitudinal sectional view of the improved bevel shearing machine forming the subject of the present invention.

35 Fig. 2 is an elevation of the machine looking from the left hand side of Fig. 1, and indicating the distant gearing in dotted lines.

Fig. 3 is a fragmentary horizontal cross section illustrating the mounting of the 40 guide rollers.

Fig. 4 is a cross section through a plate showing an edge beveled by the upper pair of cutters.

45 Fig. 5 is a similar view of a plate after its edge has been beveled by the lower pair of cutters.

Fig. 6 is a top plan view of the plate of Figs. 4 and 5, showing the beveling of all four edges.

50 The numeral 10 designates the main frame of the machine of the invention, which frame is designed to enclose substantially all the moving parts of the machine except the cutters and the driving gear. A pair of alined bearings 11 and 12 is provided on the frame to support a main shaft 13 extending hori-

zontally through the machine from one end to the other. Upon the forward end of shaft 13 a cutter 14 is mounted, being removably held upon the shaft by a nut 15. 60 The cutter 14 is beveled along both edges, as shown, and is designed to cooperate with upper and lower auxiliary cutters to effect beveling of the edges of plates and bars.

Standards 18 and 19, joined together by a base, are provided for supporting the bearings of the drive gear. These standards may be formed integrally with the main frame of the machine, or may constitute an independent supporting unit. The standard 18 has a bearing 20 at its upper end and the standard 19 has an alined bearing 20^a, a countershaft 21 being supported within these two bearings. Upon the countershaft 21 a gear 23 is mounted, such gear preferably being located intermediate of the two bearings 20 and 20^a. At one end of shaft 21 there is a pinion 22 meshing with a spur gear 17 secured upon the main shaft 13. In this way, rotation of the gear 23 effects rotation of the main shaft 13, though at a considerably reduced speed. The spur gear 17 is held upon the main shaft by a nut 26.

The upper end of the standard 19 has a bearing 27 formed thereon for receiving one end of an extension 28 of the main shaft 13. An arbor 25 is carried by the extension 28 and has secured thereon a pinion 24 adapted to mesh with the gear 23. Fast upon the arbor 25 are two tight pulleys 29 and 31, 90 while a loosely mounted pulley 30 is located between the pulleys 29 and 31. The machine is to be driven by a belt engaging with one of the pulleys, turning the same in the direction indicated by the arrow heads. It 95 will be clear that rotation of either of the tight pulleys causes corresponding rotation of the pinion 24 with consequent revolution of the main shaft of the machine.

Instead of employing a belt and pulleys, a 100 reversible motor may be mounted adjacent the machine with its pinion meshing with the gear 23. Since the particular means for driving the beveling shears forms no part of the present invention, further details of 105 such means are omitted.

A bevel gear 16 is keyed upon the shaft 13 between bearing 12 and spur gear 17, this bevel gear being rotated once with each revolution of the spur gear. The lower part 110 of the main frame of the machine has a semi-cylindrical inwardly-directed member 32

which mounts and partly encloses an auxiliary frame 33, a pivotal element 34 providing a hinge for the auxiliary frame. The auxiliary frame is preferably cylindrical and has bearings for an auxiliary shaft 36 extending the length of the frame and beyond each end thereof. The lower end of shaft 36 carries a bevel gear 37 held upon the shaft by a nut 38, the bevel gear 37 meshing with the bevel gear 16. The upper end of auxiliary frame 33 is supported by a set screw 35 which provides adjustable means for moving the auxiliary frame 33 within the space 42 afforded by the frame member 32. The shaft 36 has a collar 39 preventing longitudinal movement of the shaft downwardly. A disk cutter 40 is secured to the shaft adjacent the collar 39. At the extreme outer or upper end of the shaft 36 a bevel roller 41 is mounted, said roller constituting a supporting or "hold-up" wheel and being loosely mounted on the shaft.

The upper part of the main frame has a semi-cylindrical member 43 similar to member 32 and providing a housing for an upper auxiliary frame 44 hinged upon a pivotal element 45. An auxiliary shaft 46 is received within the frame 44, which shaft 30 carries a bevel gear 47 at its upper end, a nut 48 holding the bevel gear in place. The bevel gear 47 meshes with the bevel gear 16 so as to be driven thereby. The three bevel gears 16, 37 and 47 are of the same size whereby the shafts 13, 36 and 46 are rotated at the same speed with the gears 37 and 47 turning in a direction opposite to the direction in which shaft 13 turns. The lower end of shaft 46 carries a collar 46^a analogous to the collar 39. A disk cutter 57 similar to cutter 40 is also mounted on shaft 46 adjacent the collar 46^a.

As seen in Fig. 2, a U-shaped frame 57 is pivoted upon the main frame of the machine by studs 59, and which passes around the lower end of the auxiliary frame 44 to provide a support for such end. A beveled "hold-down" wheel or roller 52 is held by a headed stud 52^a upon the intermediate part 50 of the U-shaped member 57, the roller 52 being loose upon the stud so as to rotate thereon independently of any movement of the shaft 46. The U-shaped frame 57 is supported in adjusted positions relative to the main frame of the machine by upper and lower pairs of set screws 58 and 58^a. Lugs or ears 56 joined to the member 43 of the frame provide means for holding the upper adjusting screws 58, the lower ends 60 of which bear upon the upper edges of the arms of the U-shaped member. A set screw 49 is passed through the member 43 and bears against the auxiliary frame 44. The U-shaped frame member 57 may be swung upwardly or removed altogether from the

machine, if desired. In case the flanges of boiler heads, domes or angle bars are to be beveled, the removability of the U-shaped holder and wheel is a valuable feature. Both wheels 41 and 52 are removable and replaceable by other wheels of varying diameter, though all such wheels should be beveled as shown in order to either hold down or hold up the work in proper relation to the upper or lower pairs of cutters, as the case may be.

A stud 53 is passed through the member 43 and is engaged with the hinged frame member 44. A spring 54 surrounds the stud or bolt 53, and a nut and washer 55 are provided on the outer end of the bolt to hold the coil spring thereon. The spring 54 holds the auxiliary frame 44 up and prevents it from falling to its lowermost working position.

On each side of the cutters and supported on the main frame by brackets 63 are guide rollers 60, such guide rollers being held upon the outer ends of the bifurcated members 61, which, in turn, are adjusted within the brackets by hand wheels 62 having screw threaded shanks and engaging with the bifurcated members 61. The rollers both lie in the same vertical plane and may be adjusted instantly during the process of beveling, if necessary, by merely turning the hand wheels. The function of these guide rollers is to regulate the width of the shaving cut off from the piece being beveled and to prevent the piece from creeping in toward the bed of the machine.

The operation of the machine will now be described. If a plate is to be beveled as indicated in Fig. 4, the plate is entered between the upper pair of cutting disks 51, 14. If the plate is to be beveled as indicated in Fig. 5, the motor or driving belt will be reversed and the piece entered between the lower pair of cutters 40, 14. The beveled edge 65^a is produced by the upper pair of cutters rotating in one direction while the beveled edge 55^b is produced by the lower pair of cutters rotated in the reverse direction. The plate 65 may be beveled as indicated in Fig. 6 without turning it over by using the machine of the present invention. Where plates are very large and heavy, a great deal of time and labor is necessary to permit the turning over of the same. In the case of a very long bar it is frequently necessary to take it out of the shop to permit turning it over end for end, thereby losing much time and involving considerable outlay of labor. By the machine of the present invention, the two pairs of disk cutters rotatable in either direction allow the beveling of the edges of all sorts of structural shapes without turning the plates, bars or the like over or end for end. It is this characteristic of the present ma-

chine, which is believed to distinguish it from all other machines of this general type.

What is claimed is:—

1. In a bevel shearing machine, a main frame, a main shaft, a pair of auxiliary frames hingedly mounted on the main frame, a shaft journaled in each auxiliary frame, beveling cutters on the corresponding ends of each shaft, and means for rotating the three shafts in unison, whereby the edges of plates or bars may be beveled in opposite directions without necessitating the turning over of the plates or turning end for end of the bars.
2. In a bevel shearing machine, a main frame, a main shaft, a pair of auxiliary frames hingedly mounted at one end on the main frame, a shaft journaled in each auxiliary frame, a beveling cutter on one end of each shaft, means for adjusting the positions of the free ends of the auxiliary frames whereby the cutters on the shafts in the auxiliary frames are moved toward or from the cutter on the main shaft, and means for rotating the three shafts in unison, whereby the edges of plates or bars may be beveled in opposite directions without necessitating the turning over of the plates or turning end for end of the bars.
3. In a bevel shearing machine, a frame, a main shaft, a rotary cutter mounted on one end of said shaft, a pair of auxiliary rotary beveling cutters mounted above and below the first-named cutter, and means for rotating the three cutters in unison, whereby the edges of plates or bars may be beveled in opposite directions without necessitating the turning over of the plates or turning end for end of the bars.
4. In a bevel shearing machine, a frame, a main shaft, a rotary cutter mounted on one end of said shaft, a pair of auxiliary rotary cutters mounted one above and one below the first-named cutter, means for adjusting the vertical positions of the auxiliary cutters toward and from the intermediate cutter, and means for rotating the three cutters in unison and at the same speed with the pairs of adjacent cutters rotating in opposite directions, said auxiliary cutters rotating in planes inclined with respect to the vertical.
5. In a bevel shearing machine, a frame, a main shaft, a rotary cutter mounted on one end of said shaft, a pair of auxiliary rotary cutters mounted above and below the first-named cutter, and means for rotating the three cutters in unison and at the same speed with the pairs of adjacent cutters rotating in opposite directions, said auxiliary cutters rotating in planes inclined with respect to the vertical and at an angle to each other.
6. In a bevel shearing machine, a main shaft, a main frame, a pair of auxiliary
7. In a bevel shearing machine, a main frame, a main shaft, a pair of auxiliary frames mounted at one end on the main frame, a shaft journaled in each auxiliary frame, cutters on the corresponding ends of each shaft, means for rotating the three shafts in unison, means for effecting reversing of the direction of rotation of the shafts, the three shafts lying in the same vertical plane and the auxiliary cutters lying in planes divergent outwardly with respect to the machine.
8. In a bevel shearing machine, a frame, a main shaft, a rotary cutter mounted on one end of said shaft and rotating in a vertical plane, a pair of auxiliary rotary cutters mounted above and below the first-named cutter, means for adjusting the vertical positions of the auxiliary cutters toward and from the intermediate cutter, and means for rotating the three cutters in unison and at the same speed with the pairs of adjacent cutters rotating in opposite directions, said auxiliary cutters rotating in planes inclined with respect to the vertical.
9. In a bevel shearing machine, a main frame, a main shaft, a pair of auxiliary frames hingedly mounted on the main frame, a shaft journaled in each auxiliary frame, cutters arranged to cut a strip of material on a bevel on one end of each shaft, means for adjusting the vertical positions of the auxiliary cutters toward and from the intermediate cutter, means for rotating the three shafts in unison whereby adjacent pairs of cutters are rotated in opposite directions, and means for reversing the direction of rotation of the cutters whereby beveling may be accomplished in opposite directions without turning over the work.
10. In a bevel shearing machine, a main frame, a main shaft, a pair of auxiliary frames mounted on the main frame, a shaft journaled in each auxiliary frame, cutters on one end of each shaft, wheels or rollers associated with the cutters on the auxiliary shafts but rotatable independently thereof and adapted to hold up and hold down the work as the case may be, and means for rotating the three cutters in unison.
11. In a bevel shearing machine, a frame, a main shaft, a rotary cutter mounted on one end of said shaft, a pair of auxiliary rotary cutters mounted above and below the

120

125

130

first-named cutter, means for rotating the three cutters in unison, rotatable means associated with each auxiliary cutter but independent thereof for holding up and holding down the work against adjacent pairs of cutters, and means for adjusting the positions of the auxiliary cutters toward and from the main shaft cutter.

12. In a bevel shearing machine, a frame, 10 a main shaft, a rotary cutter mounted on one end of said shaft, a pair of auxiliary rotary cutters mounted above and below the first-named cutter, means for rotating the three cutters in unison and at the same speed 15 with the pairs of adjacent cutters rotating in opposite directions, said auxiliary cutters rotating in planes inclined with respect to the vertical, and rotatable means associated with each auxiliary cutter but independent 20 thereof for holding up and holding down the work against adjacent pairs of cutters.

13. In a bevel shearing machine, a main frame, a main shaft, a pair of auxiliary frames hingedly mounted on the main frame, 25 a shaft journaled in each auxiliary frame, cutters on one end of each shaft, means for rotating the three shafts in unison whereby adjacent pairs of cutters are rotated in opposite directions, means for reversing the direction of rotation of the cutters whereby 30 beveling in opposite directions may be accomplished without turning over the work, and wheels or rollers associated with the cutters on the auxiliary shaft but rotatable in-

dependently thereof and adapted to hold up 35 and hold down the work as the case may be.

14. In a bevel shearing machine, a main frame, a main shaft, a pair of auxiliary frames hingedly mounted on the main frame, a shaft journaled in each auxiliary frame, 40 cutters secured on the corresponding end of each shaft, means for rotating the three shafts in unison, a U-shaped frame pivotally mounted in surrounding or enclosing relation relative to the upper auxiliary 45 frame and provided with means for adjusting its position, and a roller or wheel mounted on the U-shaped frame for holding down the work, said U-shaped frame providing means whereby the hold-down roller 50 may be adjusted in the proper working position or moved out of the way of the work.

15. In a bevel shearing machine, a frame, a main shaft, a rotary cutter mounted on one end of said shaft, a pair of auxiliary rotary cutters mounted above and below the first-named cutter, means for rotating the three cutters in unison, a work holding roller associated with each auxiliary cutter, each roller being beveled whereby the work-engaging portion of the face of each roller lies in a horizontal plane. 55

In testimony that we claim the foregoing as our own, we have hereto affixed our signatures.

ALBERT R. ROBERTS.
GEORGE T. SMITH.
